DESIGN FOR A MANICURING DEVICE OR SIMILAR ARTICLE

Abraham Moses Baker, Providence, R. I.

Application June 15, 1944, Serial No. 114,015

Term of patent 14 years

(CL. D86—10)

To all whom it may concern:

Be it known that I, Abraham Moses Baker, a citizen of the United States, residing at Providence, in the county of Providence and State of Rhode Island, have invented a new, original, and ornamental Design for a Manicuring Device or Similar Article, of which the following is a specification, reference being had to the accompanying drawing, forming a part thereof.

I claim:

The ornamental design for a manicuring device or similar article, as shown.

ABRAHAM M. BAKER.
